UNITED STATES PATENT OFFICE

2,584,215

CRAVAT CLASP

Clement S. Marien, Attleboro, Mass., assignor to
Swank, Inc., a corporation of Delaware

Application November 24, 1950, Serial No. 197,333

4 Claims. (Cl. 24—49)

1

This invention relates to a clasp, such for instance as may be used for gripping a necktie and shirt, to hold the same assembled or for gripping a collar for use as a collar holder.

Clasps of this general character are usually formed by a pair of resilient jaws which have an opening into which the fabric must be forced to spread the jaws, in order that the object may have a grip upon the fabric. Thus, in many instances where the fabric is of thin character, the fabric does not form a sufficient support for its edgewise movement between the resilient jaws.

One of the objects of this invention is to provide a clasp which will open so that the fabric may be freely and easily inserted between the jaws and thereafter a grip may be provided on the fabric to maintain the fabric in position between the jaws.

Another object of this invention is to provide an arrangement so that by pressure at a certain location, the parts that grip the fabric may be released.

Another object of this invention is to provide a release of the gripping parts on the fabric by a locking action of the parts, in effect camming them into open position.

With these and other objects in view, the invention consists of certain novel features of construction as will be more fully described and particularly pointed out in the appended claims.

Figure 1 is an elevation showing the front of the clasp as positioned on a necktie with a portion of the shirt indicated beneath the tie.

Figure 2 is a view, similar to Figure 1, but showing the clasp alone and on a larger scale.

Figure 3 is an edge view looking at the clasp, as shown in Figure 2, from the lower edge thereof.

Figure 4 is a view similar to Figure 3, but illustrating the clasp as moved to a position just prior to release of the clamping member.

Figure 5 is an edge view partly in section illustrating the clamping member in open position, and the jaw open for receiving the fabric which is shown in Figure 1.

Figure 6 is an edge view on substantially line 6—6 of Figure 1, showing the application of pressure for releasing the clamping member.

Figure 7 is a section on line 7—7 of Figure 3.

Figure 8 is an elevation of the back of the clasp.

In proceeding with this invention, I provide a pair of jaws which are at an angle to each other, and so spaced that the fabric which is to be gripped may be placed between them without exerting any tendency to spread the jaw apart. I provide a clamping member, pivoted to the free

2

end of one of the jaws, which will swing toward the other jaw, spanning the jaw to which it is pivoted so as to grip the fabric between it and the other jaw. The clamping member is provided with detents to hold it in clasped position.

With reference to the drawings, a portion of a shirt is designated 10, having a binding 11, and button 12, which binding is attached to the portion of the shirt 13, and overlaps the portion of

10 the shirt 14. The necktie is designated 15, and a clasp designated generally 16, which is the subject of this invention, grips the binding 11 of the shirt, and the necktie holding the necktie in clamped position on the shirt.

15 This clasp 16 comprised a front jaw 17 and a back jaw 18 (Fig. 5) which jaws are connected together by a bight portion 19, which may be formed by bending of the stock so as to form the two jaws. The jaws 17 and 18 normally flare 20 apart, as shown in Figure 5, so as to provide their free ends 20 and 21 in a sufficiently spaced relation for receiving the fabric 11 and 15 between them. The back jaw 18 is sufficiently flexible so it may be easily flexed to move toward the heavier 25 and the more rigid jaw 17 by bending along its length, and also the adjacent bite 19. The front jaw 17 is a width substantially wider than the rear jaw, as may be seen in Fig. 7.

A clamping member is designated generally 22, 30 comprising a strip of metal 23 with flanges 24 bent up on either side to form a generally channel section, as shown in Figure 7. The flanges are arcuate along their edge 25 and are serrated or provided with teeth 26. The stock of the rear jaw 28 is cut away, as at 26, and a tongue 27 is formed on the portion 23 of the clamping member 22, and rolled about the cross bar formed by the cut-out 26 in the back jaw, so as to provide 35 a hinged connection therewith.

40 The opposite or free end of the clamping member is provided with inwardly extending detents 28 so as to snap over the edges of the jaw 18 when swung about its pivot, and pressure is applied to force the detents over the edge thereof.

In use, the clamping member 22 is swung to open position, as shown in Fig. 5, so as to leave the flaring jaws 17 and 18 in a open mouth-like position to receive the fabric 11 and 15 between them, after which the clamping member 22 is 50 swung about its hinge to cause the serrated arcuate portions to engage the fabric, pressing it against the inner surface of the front jaw 17, and if necessary flex the rear jaw 18 in order to accomplish this, so that a pressure is applied 55 throughout the spring of the rear jaw to hold

the parts in clamped position. When it is desired to release the clamping member, it is necessary to apply pressure at its hinged connection 27, which causes the member to rock about a fulcrum point, such as 30, along its arched edge, and rock or roll the clamping member 22 so as to spring the detents 28 over the edge of the jaw 18, and release the member from clamping position, whereupon by reason of its free pivoting, it is swung outwardly to the position shown in Figure 5, and the clasp may be readily withdrawn from the fabric on which it is mounted.

I claim:

1. A clasp for jewelry of the like comprising a pair of jaws resiliently connected at one end and spaced at their other free ends to receive between them material to be held, and a clamping member pivoted to the free end of one of said jaws to swing to and from the outer surface of the jaw to which it is pivoted, said member having a flange located beyond the edge of the jaw on which it is pivoted to extend toward the inner surface of the other jaw sufficiently to bind material between the jaws and resilient means adjacent the free end of the clamping member to hold the same in clamping position.

2. A clasp as in claim 1 wherein said resilient means comprises a detent to snap over the edge of the jaw on which it is pivoted.

3. A clasp as in claim 1 wherein the jaw opposite the jaw on which said member is pivoted is wider than said member to present a broad clamping inner surface.

4. A clasp as in claim 1 wherein the flange of said member is arcuate and engages the work to be clamped intermediate its ends to provide a fulcrum point.
